RAILWAY CAR SIDE PLATE

Raymond M. Shaver, Michigan City, Ind., Archie M. Miers, Homewood, Ill., and Franklin P. Adler and Gulow K. Jorgensen, Michigan City, Ind., assignors to Pullman Incorporated, a corporation of Delaware

Filed June 9, 1954, Ser. No. 435,526
1 Claim. (Cl. 104—409)

This invention relates to improvements in railway box car construction and more particularly to an improved side plate construction. Principal objects of the invention are to provide a sufficient section beyond the rivet joint for proper sealing to prevent leakage, to provide for easier fitting up of the roof, and to provide means for directing foreign matter away from the roof and side plate seal.

The invention consists in the construction and combined arrangement of the parts.

These and other objects will be noted from the following description and the accompanying drawings, wherein:

FIG. 1 is a fragmentary transverse vertical sectional view of a box car at the junction of the roof structure and side wall structure;

FIG. 2 is a sectional view similar to FIG. 1 and depicting a first slightly modified side plate;

FIG. 3 is a sectional view similar to FIG. 1 and depicting a second slightly modified side plate;

FIG. 4 is a sectional view similar to FIG. 1 and depicting a third slightly modified side plate; and

FIG. 5 is a sectional view similar to FIG. 1 and depicting a fourth slightly modified side plate.

Referring now to FIG. 1, the structural arrangement of a box car roof joined to the side wall of the car is illustrated, wherein the roof is comprised of a seam cap 10 and a roof sheet 11 being joined to a pressed side plate 12 by means of a rivet 13. The side plate 12 is secured to a side post 14 by means of welding 15. The outer side wall sheathing 16 and inner lining 17 are illustrated in place, along with the car inner end wall 18. As shown, the side post, roof structure (sheet and cap), and side plate, are all formed of metal.

Although the embodiment herein depicted includes a seam cap 10, it is of course known to those versed in the art that various sections of the roof-side plate juncture do not include the seam cap.

The side plate 12 in FIG. 1 is of integral, one-piece construction and has a "question mark" configuration in cross section wherein a vertically disposed lower flange or portion 19 is joined at its top by a substantially horizontal portion 20 which extends inwardly substantially the transverse width of the side post 14. A vertical upstanding portion 21 extending from the inner edge of the portion 20 is joined at its top to an outwardly and downwardly declining portion 22 which contacts and follows the pitch of the roof sheet 11. Depending from the outer edge of portion 22 is an angularly declining portion 23, to which the end 24 of the seam cap and the flange 25 of the roof sheet 11 are joined by the rivet 13. It is to be noted that the horizontal space between the portion 21 and the most extended point of the portion 23 is substantially equal to the transverse width of the post 14, as is the width of the horizontal portion 20. This provides sufficient working space for the riveting operation.

The advantages of such an arrangement are manifold. Whereas some of the present day arrangements develop leakage points due to insufficient sealing area between the side plate 12 and the roof sheet 11, the present arrangement provides sufficient area therebetween for proper sealing. Some present day arrangements also have the rivet placed in a high shear area and receiving no structural help from the roof structure. By adding the depending por-

2

tion 23 of the side plate, the seam cap 10 and roof sheet 11 help hold the roof and car side together by a hook action instead of depending practically entirely upon shear action of the rivets 13. Another difficulty encountered due to present day construction, whereby a gathering place for foreign matter is presented immediately adjacent the roof and side plate outer sealing edge, is eliminated by having a smooth outer sealing edge and by directing foreign matter away from the seal, due to the particular configuration. Such configuration used herein also provides a substantially perfect guide on each side of the car for fitting the roof structure thereon.

These many advantages are also found in the four modified configurations depicted in FIGS. 2 to 5. The side plate 12a in FIG. 2 is nearly identical with that of FIG. 1 except for the portion 23a which is angularly inclined outwardly from the portion 22 rather than depending directly vertically therefrom.

The side plate 12b in FIG. 3 is nearly identical with the configuration in FIG. 1 except that the portion 20b has a shorter transverse cross-sectional length than portion 20, and portion 23 is in a longitudinally vertical plane outside of the longitudinally vertical plane of portion 19.

25 The side plate 12c in FIG. 4 is substantially identical to that of FIG. 1 except that two rolled angle members 26 and 27 are used, being secured together at weld joint 28. The upper angle 27 has had the legs 29 and 30 thereof bent to form an acute angle, and a portion of leg 30 bent downwardly to form a flange 31, the flange being substantially parallel to the vertical leg 29 and inwardly of the depending flange or leg of the lower angle member 26.

35 The side plate 12d in FIG. 5 is substantially identical to that of FIG. 1 except that the portion 22d declining outwardly from the upstanding portion 21d is shortened and may be arched, and the depending portion 23d has an outwardly extending downwardly offset flange 32, lying in a plane substantially parallel with that of the inwardly extending portion 20d. A pocket for the sealing compound 33 is formed by this particular configuration, adding the advantage of preventing the sealing compound from being knocked off during assembly of the roof sheet 11 to the side plate 12d.

45 It may be noted here that while the portion 20 of the side plate 12 of FIG. 1 and the corresponding portions of the constructions shown in FIGS. 2 and 3 are fairly described as substantially horizontal, they do have an outward and downward slope or pitch, as shown. The horizontal leg or flange of the angle member 26 in FIG. 4 is not illustrated as so sloped.

What is claimed is:

In a car construction having metal parts including a side post, a roof structure, and a side plate, said side plate comprising an integral one-piece structure including a flat vertical portion depending below the top of said side post and having its inner surface positioned against and secured to said side post by means of welding, a portion extending inwardly from the top of said vertical portion substantially the width of said side post transversely of the car, a portion upstanding from the inner end of said inwardly extending portion, a supporting portion declining generally outwardly from the upper end of said upstanding portion, an attaching portion sloping outwardly and downwardly from the outer end of said supporting portion forming an inner obtuse angle thereto and terminating substantially in vertical alignment with said vertical portion at a location spaced above the inwardly extending portion, said roof structure being supported in direct contact with said supporting portion and in sealing contact with said attaching portion, and securing means penetrating the roof structure and the attaching portion and being

headed so as directly to secure the roof structure to the attaching portion.
